UNITED STATES PATENT OFFICE.

JAMES A. NILES, OF LYNN, MASSACHUSETTS.

SHOE-FORM.

1,079,429.

Specification of Letters Patent.

Patented Nov. 25, 1913.

Application filed November 16, 1912. Serial No. 731,909.

To all whom it may concern:

Be it known that I, JAMES A. NILES, of Lynn, in the county of Essex and State of Massachusetts, have invented new and useful Improvements in Shoe-Forms, of which the following, taken in connection with the accompanying drawings, is a specification.

The present invention relates to improvements in bottomless shoe forms for boots and shoes and more particularly to shoe forms made of fiber or other light sheet materials and used for followers in shoe factories and for insertion in boots and shoes for display and advertising purposes and 15 to keep in shape boots and shoes when out of wear without wrinkle, crease or slumping of the upper leather, and so preserve their shape particularly when the leather is wet.

The object of this invention is to construct 20 a bottomless shoe form out of one entire piece of crimped fiber or other light sheet material without cuts or laps from heel to toe and particularly without cut or lap on the ellipse shaped cone or top above the 25 shank and heel parts in combination with a heel which is shaped by the folded parts of the entire fiber out of which the form is made and fastened in the upper part of the heel so that the lower part of the heel is 30 unsecured, in order that the sides of the heel below where it is fastened shall yield to pressure transversely applied from without when the form is inserted in the shoe or when it is withdrawn therefrom. This enables the person inserting or removing the 35 form from a shoe to do so with greater ease. There is also a form of heel answering to above description and covered by this patent which is particularly strong and useful for 40 the purposes of this invention because the shape of the heel is obtained by means of a tongue of unbroken fiber cut from the fiber of which the form is made and which is bent down over the edges adjacent to it 45 which are folded under it, all three parts being secured by a rivet which pierces all of them in the upper part of the heel, as is more particularly hereinafter described. The pressure exerted by the sides of the 50 heel below the point of fastening after the form is inserted in the shoe is slight as they are in contact with the parts of the shoe supported by the heel counter while the firmer part of the heel holds the shank and

toe parts of the form and the parts between the same fully in position against the inside of the shoe.

The flat or nearly flat ellipse shaped cone on this shoe form gives owners, dealers and manufacturers an opportunity to print, 60 stamp or engrave their names on the forms in a conspicuous way to indicate their ownership of the forms for advertising purposes or for personal use.

Figure 1, is an interior view of the shoe 65 form. Fig. 2, is a view of the form inserted in the shoe. Fig. 3 outlines a strip of fiber the tongue *e* of which is to be folded over the edges *f f* as they are overlapped so as to bring one edge *g* overlapping; Fig. 4, 70 is a plan view of the body of the heel and shanks of the shoe form.

Referring to the drawings: Fig. 1, shows the interior of the shoe form and the under side of the cone above the shank marked *y*. 75 The form is riveted at *b* to shape the heel and fasten it in the upper part thereof leaving the lower part of the heel flexible to pressure applied transversely thereof. As shown in this figure any means of fastening 80 the upper part of the heel may be used. The special manner of shaping the form elsewhere described is not specifically covered by Fig. 1.

Fig. 2, explains the ultimate use of the 85 form and indicates by *x* the cone above the shank where the manufacturer may imprint his name for advertising purposes. The owner's name may also be printed here to indicate ownership for his personal use. 90

Fig. 3, outlines a strip of fiber with the tongue *e* folded over edges *f f* which are overlapped so as to bring one edge *g* overlapping the other edge *g* all of which parts are to be fastened together by rivet *b* as 95 shown in Fig. 4, and the line of the outer overlapping edge *g* will follow similar line to that shown by edge *g* in Fig. 4.

The rivet *b* in Fig. 4 is shown in the upper part of the heel of the form in order to 100 leave the edges *g* below it unsecured so that the sides of the heel which are unfastened in the lower part, will bend inward when pressure is transversely exerted upon them from the outside.

What I claim as my invention is as follows:

A bottomless shoe-form shaped out of a

2
single piece of material by two straight cuts on the heel-edge leaving a central tongue, the center of the lower edge of which is the center of the heel-edge; the two parts adjacent to said tongue being bent under it, overlapping each other and a rivet extending through the tongue and the two overlapped parts underneath; the unsecured lower part of the shoe-form being flexible to pressure applied transversely thereto in inserting the

shoe-form into the shoe and in withdrawing it therefrom, substantially as described.

In testimony whereof, I have signed my name to this specification in the presence of two subscribing witnesses, on this fourteenth day of November A. D. 1912.

JAMES A. NILES.
